Fig. 13. A technical drawing of a vertical component. The component has a central slot with two circular features labeled 'A' at the top and bottom. The number '2' is written twice on the left side of the slot. The number '25' is written at the bottom right. The number '27' is written at the bottom left.

3 Sheets—Sheet 3.

The image contains several technical drawings of a mechanical device, likely a lock or fastener, shown from different angles. The drawings are labeled with numbers 1 through 23.

- FIG. 14.** A side view of a cylindrical component with a slot 14 and a protrusion 15. Number 10 is at the top, and number 8 is at the bottom.
- FIG. 15.** A side view of a similar cylindrical component, showing a slot 14 and a protrusion 15. Number 10 is at the top, and number 11 is at the bottom.
- FIG. 16.** A top-down view of a rectangular frame or housing. It features a slot 14, a protrusion 15, a slot 14, a protrusion 10, a slot 14, a protrusion 8, and a slot 11.
- FIG. 17.** A cross-sectional view of the device. It shows a main body with a slot 14, a protrusion 10, a slot 14, a protrusion 8, and a slot 11. Number 3 is at the top, and number 9 is at the bottom.
- FIG. 18.** A cross-sectional view of the device, similar to FIG. 17, showing internal components 16, 18, 19, and 12.
- FIG. 19.** A cross-sectional view of the device, similar to FIG. 17, showing internal components 16, 18, 19, and 12.
- FIG. 20.** A cross-sectional view of the device, similar to FIG. 17, showing internal components 16, 18, 19, and 12.
- FIG. 21.** A cross-sectional view of the device, similar to FIG. 17, showing internal components 16, 18, 19, and 12.
- FIG. 22.** A cross-sectional view of the device, similar to FIG. 17, showing internal components 16, 18, 19, and 12.
- FIG. 23.** A cross-sectional view of the device, similar to FIG. 17, showing internal components 16, 18, 19, and 12.
- FIG. 11.** A top-down view of a component with a slot 1, a protrusion 8, a slot 9, and a protrusion 7.
- FIG. 10.** A side view of a component with a slot 14, a protrusion 8, and a slot 11.

UNITED STATES PATENT OFFICE.

MICHAEL HÄBERLE, OF BROOKLYN, NEW YORK.

WINDOW.

SPECIFICATION forming part of Letters Patent No. 699,919, dated May 13, 1902.

Application filed August 19, 1901. Serial No. 72,552. (No model.)

To all whom it may concern:

Be it known that I, MICHAEL HÄBERLE, a citizen of the United States, residing at Brooklyn, in the county of Kings and State of New York, have invented certain new and useful Improvements in Windows; and I do hereby declare the following to be a full, clear, and exact description of the invention, such as will enable others skilled in the art to which it applies to make and use the same.

This invention relates to the class of windows in which the sash are hung for swinging about a horizontal axis to admit of cleaning, replacing broken panes, ventilating, or other desired purpose and which are counterbalanced and have a free sliding movement in the casement or frame.

The invention consists of the novel features, details of construction, and combinations of the parts, which hereinafter will be more fully described, illustrated, and finally embodied in the claims.

In the drawings, Figure 1 is a front view of a window embodying the invention, a corner portion of the lower sash being broken away to show the hinge-joint between a slide-bar and the upper sash. Fig. 2 is a plan section about on the line X X of Fig. 1, on a larger scale, an intermediate portion being broken away. Fig. 3 is a detail perspective view showing the means for preventing inward movement of the upper ends of the slide-bars when the sash is swung open. Fig. 4 is a detail perspective view of the fastening between a sash and the upper portion of the slide-bars, the parts of the fastening being separated. Fig. 5 is a detail perspective view showing the relation of the parts when the sash is swung open. Fig. 6 is a vertical section on the line Y Y of Fig. 1, on a larger scale, the upper and lower sash being shown swung open by full lines and the lower sash being shown partially open by dotted lines. Fig. 7 is a detail perspective view of the form of slide-block for use in connection with a chain. Fig. 8 is a detail view of the end portion of a brace-bar having connection with a slide-block. Fig. 9 is a detail perspective view of the lock-pin, escutcheon-plate, and portion of the stile to which the lock-pin and plate are applied. Fig. 10 is a detail view showing more clearly the disposition of the

slide-block, brace-bar, lock-pin, and adjunctive parts. Fig. 11 is a detail view showing the connection between a brace-bar and 55 slide-block on a larger scale. Fig. 12 is a detail view showing the hinge connection between a slide-bar and sash, parts being broken away about on the line Z Z of Fig. 13. Fig. 13 is an elevation of a slide-bar, showing 60 the hinge connection applied thereto illustrated in Fig. 12. Fig. 14 is a detail view in elevation of a portion of a slide-bar, showing a modified form of slide-block for the attachment of a rope thereto. Fig. 15 is a section 65 on the line W W of Fig. 14. Fig. 16 is a section on the line V V of Fig. 14. Fig. 17 is a perspective view of the slide-block shown in Figs. 14, 15, and 16.

Corresponding and like parts are referred 70 to in the following description and indicated in all the views of the drawings by the same reference characters.

The window frame or casement 1 may be of any construction and size and is provided 75 with upper and lower sliding sashes counterbalanced in any selected way. The sashes are similarly mounted so as to swing from the vertical about a horizontal axis to admit of the panes or lights being readily reached for 80 cleaning or other desired purpose. The sashes are hinged at their lower ends to the slideable bars either directly or by means of a connecting cross-bar. The slideable bars 2, one for each side of the frame or casement and a 85 pair for each sash, are arranged in the spaces or vertical guide-grooves provided between the stops of the casement, and the counterbalance is connected directly thereto either by means of a chain or cord. Inasmuch as 90 each slideable bar and the adjunctive parts are similarly constructed, a detailed description of one only will be given. The slideable bar 2 has a vertical slot 3, which is enlarged at one end to admit of the head of the slide-block 4 passing therethrough when placing the slide-block in position for running movement in the vertical slot. Opposite sides of the bar 2 are cut away, and the side adjacent the jamb of the casement is grooved to receive the chain, cord, or like connection between the counterbalance and the slide-block. The lower end of corresponding bars 2 has connection with the lower end of the sash and 95 100

is prevented from inward displacement, and in order to prevent inward movement of the upper ends of the bars 2 when the sash is swung from a vertical position keepers 5 are secured to the upper ends of the bars 2 and have projecting ends, which enter and operate in grooves 6, formed in the inner sides of the stops. A bar 7 connects the sash with the slide-block 4 and limits the swinging movement of the sash. This bar 7 has pivotal connection at one end with a stile of the sash, and its opposite end has pivotal connection with the slide-block. A T-shaped lug 8 is provided upon the side of the block 4, designed to face the window-opening and cooperates with an opening 9 to pivotally connect the bar 7 to the slide-block. The opening 9 is oblong and arranged crosswise of the bar 7 and is medially arranged with reference to a round countersink formed in a side of the said bar to receive the arms of the lug 8 and admit of the end of said lug coming flush with the side of the bar 7. When the bar 7 is turned to bring the opening 9 in coincident relation with the T-shaped lug 8, the bar may be fitted to or removed from the slide-block, and when fitted to the said slide-block and the lug 8 has passed through the opening 9 a turning of the bar 7 will cause the arms of the lug 8 to engage with the countersinks at the sides of the said opening 9 and prevent separation of the parts 4 and 7. The bar 7 is of a width to overlap the edge of the vertical slot 3 and prevent outward displacement of the slide-block 4. Inward movement of the slide-block is prevented by oppositely-disposed wings 10 at opposite ends of the block. Opposite wings or extensions 11 are provided at the inner side of the block at the end opposite the lug 8 and constitutes a head to overlap the sides of the slot 3 and in conjunction with the bar 7 prevent outward displacement of the slide-block. This head 11 is adapted to pass through the enlarged end or portion of the slot 3 when placing the slide-block in position or removing it from the slide-bar 2.

When a chain 12 is employed as the connecting means between the counterbalance and the slide-block, the latter is formed with an apertured ear 13 for connection of the chain therewith; but when a cord or rope 14 is employed for connecting the counterbalance to the slide-block the latter is modified in construction to the extent of replacing the apertured ear 13 by a notched lug 15 for the reception of the said cord, the knot lying in the space formed between the lug 15 and the end portions of the block carrying the T-shaped lug 8. By having the lug 15 notched in its side the cord or rope can be readily placed in position or removed from the block without the inconvenience resulting from such constructions as require the threading 65 of the cord through an opening or passage. The open side of the notch is closed by a side

of the slot 3, into which the notched lug extends when the slide-block is in position.

The fastening means for connecting the swinging end of the sash to the free ends of the slide-bars consist of complementary members 16 and a lock-pin 17. The members 16 are of like construction and are formed with projections 18, which are beveled upon the sides adjacent the part to which the members are attached, so that when closing the sash the slide-bars are simultaneously drawn close against the edges of the said stiles. These beveled projections overlap when the sash is closed and have corresponding openings 19 to receive the inner end of the lock-pin 17, which is slidably mounted in the side stile of the sash. By having the lock-pin pass through the beveled projections 18 of the members 16 of the fastening the opening in the slide-bar 85 and side stile of the sash is not enlarged or worn, the parts 16 acting as wear-plates. One end of the lock-pin is bent to provide a finger-grip 20, and the opposite end is rounding, so as to pass through the openings 19 and snugly fit the same, so as to prevent any possible movement of the sash with reference to the corresponding slide-bars. The intermediate portion of the lock-pin is flattened, as shown at 21, and operates 95 in the narrow portion of the keyhole-slot 22, formed in the plate 23, attached to the side stile of the sash. By having the flattened part 21 of the lock-pin arranged to operate in the narrow portion of the keyhole-slot 22 the finger-grip 20 is maintained in a given position and the lock-pin is limited in its sliding movements. The enlarged end of the keyhole-slot 22 of the plate 23 is out of register with the opening in the side stile of the sash when the 105 said plate 23 is secured thereto.

The slideable bars 2 are connected with the sash, so as to move in unison, thereby preventing any binding of the sash or slide-bars when moved up or down in the frame or casing. In the case of a direct connection between the sash and slide-bars the means consist of members 24 and 25, pivotally connected, the member 24 being rigidly attached to the slide-bar and the member 25 being firmly 110 attached to the horizontal rail of the sash. Each member of the hinge connection comprises right-angularly-disposed parts, a boss or reinforcement 26 being formed or provided in the angle between the parts and these reinforcements 26 being apertured in coincident relation to receive the pivot-pin 27. The hinge connection is such that when properly applied the sash and slide-bars must move up and down in a manner similar to a rigid 115 structure. The vertical portions of the hinge members are let into mortises and slide-bars so as to come flush therewith and admit of these parts coming close together. In another form corresponding slide-bars 2 are connected at one end by means of a cross-bar 28, which is rigidly attached at its ends to the 120 125 130

bars 2 in any substantial way. The sash is hinged to the transverse connecting-bar 28 by any form of hinge 29. While the sashes can be mounted to swing either in or out or 5 up or down, it is preferred to have them swing inward and downward.

By having the swinging sashes connected to the slide-blocks by means of the brace-bars 7 and by having the counterbalancing means 10 connected with the said slide-blocks the counterbalance in addition to holding the sash at any elevation also serves to materially assist in holding the sash open to any desired angular adjustment and facilitates the swinging 15 of the sash when opening and closing it by a swinging movement.

The inner stop of the casement has a vertical groove 30, which is adapted to coöperate with the lock-pin so as to hold either sash 20 open for ventilating purposes and prevent its closing by a draft. When the sash is swung inward at its upper end and the inner end of the lock-pin 17 is entered into the vertical groove 30, the sash cannot be closed or opened 25 farther by means of a draft, and this is of material advantage in stormy weather. The provision of the vertical groove 30 admits of the sash being moved up and down without necessitating the closing or swinging of the 30 sash into the plane of the slide-bars 2.

Having thus described the invention, what is claimed as new is—

1. In a window, and in combination with 35 slideable bars, a sash having hinged connection therewith, and a slide-block having a T-shaped lug, a brace-bar having pivotal connection at one end with the sash and provided at its opposite end with an oblong opening and a round countersink for reception of the 40 arms of the T-shaped lug after the latter has passed through the said oblong opening, substantially as set forth.

2. In a window, and in combination with 45 slideable bars, and a sash having hinged connection therewith, a fastening comprising complementary members secured to, respec-

tively, the slideable bars and side stiles of the sash and having coöoperating beveled portions, and a lock-pin applied to a side stile of the sash to pass through corresponding openings 50 in the said members of the fastening, substantially as set forth.

3. In a window, and in combination with slideable bars, and a sash having hinged connection thereto, a lock-pin slidably mounted 55 in an opening formed in a side stile of the sash for securing the latter when closed, said pin having an intermediate flattened portion, and an escutcheon-plate having a keyhole-slot and secured to the side stile of the sash 60 with the flattened portion of the lock-pin arranged to operate in the contracted portion of the said keyhole-slot, substantially as and for the purpose set forth.

4. In a window, and in combination with 65 slideable bars having vertical slots, a sash having hinged connection with the said bars so as to swing open and shut, slide-blocks having notched lugs for reception of the knotted end of the rope or cord leading from the 70 counterbalance, said blocks mounted for sliding movement in the aforesaid vertical slots and having the open sides of the notches closed by a side of the said slots, and brace-bars connecting the slide-blocks with the 75 hinged sash, substantially as set forth.

5. In a window, and in combination with the casement having a vertical groove, slideable bars, and a sash having hinged connection with said slideable bars, a lock-pin applied to the sash for coöperation with a slideable bar to hold the sash closed and adapted to enter the aforementioned groove for holding the sash open without interfering with its sliding movements, substantially as set forth. 85

In testimony whereof I affix my signature in presence of two witnesses.
